UNITED STATES PATENT OFFICE.

ALFRED ERNEST DROWN, OF WESTMINSTER, LONDON, ENGLAND.

GLAZING SYSTEM.

1,377,673.

Specification of Letters Patent. Patented May 10, 1921.

Application filed March 26, 1919. Serial No. 285,296.

To all whom it may concern:

Be it known that I, ALFRED ERNEST DROWN, a subject of His Majesty the King of England, and resident of Westminster, in the county of London, Kingdom of England, have invented certain new and useful Improvements in or Relating to Glazing Systems, of which the following is a specification.

10 / This invention relates to glazing systems of the kind in which the sheets of glass are retained in position on a reinforced concrete glazing bar without the use of putty or the like and the said invention has for its 15 object to provide improved means for holding the sheets of glass in position.

According to this invention the sheets of glass are retained in position against a reinforced concrete glazing bar having two 20 upper reinforcing members by retaining or securing means adapted to engage metal clips embedded in the glazing bar and suitably connected to the said reinforcing members. Each sheet of glass is preferably retained in position against two separate and 25 independent bearing surfaces, the said bearing surfaces being supported by the glazing bar. The retaining or securing means comprises a screw, bolt or equivalent passed 30 through a metal washer and a weather resisting washer on the upper faces of the glass sheets and adapted to engage a metal clip bedded in the glazing bar and connected to the two upper reinforcing members 35 thereof, a longitudinally disposed strip of bituminous felt or other weather resisting packing being interposed between the lower faces of the glass sheets and the upper face of the glazing bar. The glazing bar is provided with a centrally arranged 40 plane upper surface adapted to support the flat strip of weather resisting packing such as bituminous felt or other material, a channel or gutter and a recess on each side thereof, the said recess being adapted to receive asbestos or like packing material. If desired the centrally arranged plane upper surface of the glazing bar may be extended 45 upwardly so as to be flush or approximately flush with the upper faces of the glass sheets.

In order that the invention may be clearly understood, reference is made to the accompanying drawings whereon Figure 1 shows a vertical section of a construction in accordance with the present invention. Fig. 2

shows a vertical section of a modified construction also in accordance with the present invention.

Figs. 3, 4 and 5 are respectively a side view, an end view, and a cross section of a modified construction of the glazing bar and the retaining means shown in Fig. 1.

Referring to Fig. 1 of the drawings, 1 is a concrete glazing bar having two upper reinforcing members 2, 3 and a lower reinforcing member 4 of iron, steel or other suitable material. The upper face of the glazing bar is provided with a centrally arranged plane surface 5 on which rests a longitudinally disposed strip of weather resisting packing 6 of bitumen, bituminous felt or other suitable material. On each side of the plane surface 5 is provided a gutter 7, 8 and a recess 9, 10 into which fits asbestos packing 11, 12.

A suitable number of sheet metal clips 13 each having a tapped hole 14 is embedded in the concrete glazing bar 1 so that the upper face of the clip is flush or approximately flush with the plane face 5 of the concrete glazing bar.

The clip 13 is formed or provided with two downwardly extending prongs 15, 16 the ends of which are bent, or twisted around the upper reinforcing members 2, 3 of the concrete glazing bar, the lower reinforcing member 4 being suitably connected as by stirrups 17 to the members 2, 3. The upper part of the glazing bar and centrally thereof, is formed with a hole 18 which is intended to receive the end of a set screw 19, bolt or equivalent, the said set screw engaging the tapped hole in the clip 13 and thus binding the sheets of glass 20, 21 between the asbestos packings 11, 12, bituminous felt strip 6 and a bituminous felt washer 22 overlying the glass sheets. 23 is a metallic washer placed between the head of the set screw 19 and the washer 22.

In the construction shown in Fig. 2 the central portion of the reinforced concrete glazing bar is extended upward so that the plane face 5 may be flush or approximately flush with the upper faces of the glass sheets, the use of the longitudinally disposed bituminous felt strip 6 shown in Fig. 1 being thereby obviated and the bituminous felt washer 22 used in lieu thereof.

In the construction shown in Figs. 3, 4 and 5 the cap, or caps, or cover plate or cover plates 24 which retain the sheets 20,

21 of glass in position is or are made of asphalt, a mixture of asphalt and tar or similar material or concrete, compressed paper-pulp, imitation marble or stone or other suitable material reinforced longitudinally or vertically with single wires or with two or more stranded wires as shown at 25. The cap or cover plate may be formed as a circular, square, rectangular or oblong plate 10 and may be in lengths or sections. In a convenient form and as shown more particularly in Figs. 3 and 5, the asphalt plate 24 is of any suitable length and may be provided with a portion of suitable shape 15 projecting from the lower face of the cap 24. The metal wires 25, 26 or stranded metal wires are embedded in the asphalt at suitable distances apart, such wires being, if so desired, but not essentially interconnected by metallic or other suitable binding material 27 shown dotted in Fig. 5. If desired, the upper plane face 29 of the glazing bar 1 may project upwardly between the glass sheets as shown in Fig. 5 to a position 25 flush with the upper surface thereof, or slightly below the said surface. The lengths or strips of asphalt 24 are secured to the glazing bar 1 preferably by screws 30 adapted to engage nuts 31 embedded in the glazing bar 1 and cast or molded therewith. A washer 32 or washers of any suitable material may be interposed between the head of each screw 30 and the length 24 or strip of reinforced asphalt. 30 At suitable intervals along each inclined side of the glazing bar, recesses 33, 34 are provided, the recesses being preferably formed in the glazing bar 1 when the latter is cast or molded. The recesses 33, 34 may 35 be of any suitable depth, the characteristic feature of the recesses being that the faces 35, 36 of the recesses 33, 34 against which the brackets 37, 38 abut are vertical so as to avoid the use of angled or set-back brackets or tapered distance or filling pieces be- 40 45

tween the brackets and the glazing bar. At its lower end each recess may be flush with the lower corresponding edge of the bar as shown more particularly in Fig. 5 and the recesses may be longer, as shown in Fig. 3, 50 than their respective brackets so as to allow for adjustment of the brackets relative to the bolt holes 39 when securing the brackets and glazing bar 1 to the purlins 40 or equivalent. A plurality of bolt holes may 55 be provided in the glazing bar 1 at each recess to allow for adjustment of the bracket. Each of the brackets 33, 34 may be secured by a separate bolt and nut, but it is preferred that opposed brackets as shown be 60 secured by the same bolt 41 and nut 42.

What I claim is:—

1. The combination of a reinforced glazing bar, of glass sheets supported thereon, and means forming a fixed part of said bar 65 and secured to the reinforce member thereof to retain the glass sheets in position.
2. In combination, a reinforced concrete glazing bar, having spaced independent bearing surfaces for each sheet of glass, a 70 member embedded in said bar and connected with the reinforcing means thereof, cover plates to overlap the joint between the adjacent glass sheets, and means passed between said glass sheets through the cover plates 75 and threaded into said member.
3. The combination with a reinforced concrete glazing bar, having spaced bearing surfaces to support glass sheets, a member embedded in said bar and tied to the reinforce means thereof, cover plates to overlie 80 the glass sheets and bridge the joint between them and a bolt passed through said cover plates between the glass sheets and threaded into said member to secure the glass sheets 85 in position.

In testimony whereof I have hereunto signed my name.

ALFRED ERNEST DROWN.
